UNITED STATES PATENT OFFICE

2,462,812

THREAD-TENSION DEVICE FOR SEWING MACHINES

Frank Parry and Berthold P. Pinkvoss, Bridgeport, Conn., assignors to The Singer Manufacturing Company, Elizabeth, N. J., a corporation of New Jersey

Application February 9, 1946, Serial No. 646,603

10 Claims. (Cl. 242—150)

1

This invention relates to thread-tension devices for sewing machines and, more particularly, to thread-tension devices of the two-disk reusable type for tensioning the needle-thread.

Devices of the present type heretofore used were provided with an abutment-plate formed with a rotation-restraining finger which was adapted to enter an aperture formed in the sewing machine wall. With this type of construction there was a tendency for the abutment-plate to cant whenever the tension-spring pressure was released therefrom, and thus the rotation-restraining finger sometimes became wedged against the apertured side wall of the machine frame when the spring pressure was again applied to the abutment-plate. With the abutment-plate thus held out of its proper position, the tension unit became inoperative.

The principal object of the present invention is to provide a thread-tension unit which will overcome the above noted difficulty.

Another object of the present invention is to provide a needle-thread tension unit with means to prevent inadvertent unthreading of the check-spring.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Fig. 1 represents a face view of the needle-bar head of a sewing machine carrying a pair of tension devices embodying one form of the invention.

Fig. 2 represents a rear elevation view of the needle-bar head carrying the two-tension units.

Fig. 3 represents an enlarged side view of one form of the tension device.

Fig. 4 represents a longitudinal sectional view of the unit shown in Fig. 3.

Fig. 5 represents an enlarged view of a second form of tension device.

Fig. 6 represents a disassembled perspective view of the tension device shown in Fig. 3.

Fig. 7 represents a disassembled perspective view of elements forming a part of that device shown in Fig. 5.

Fig. 8 represents a sectional view taken substantially along line 8—8 of Fig. 4.

Fig. 9 represents a sectional view taken substantially along line 9—9 of Fig. 5.

Fig. 10 represents a longitudinal sectional view of the unit shown in Fig. 3, but with the tension disks in their separated or open position.

The sewing machine, illustrated in the drawings, has a frame including a work-supporting

2

bed-plate indicated by line 10 and a hollow bracket-arm head 11. Journaled for vertical reciprocation in the bracket-arm head 11 is a needle-bar 12 carrying at its lower end a pair of needles of which only one, designated by the numeral 13, is shown, said needle-bar 12 being endwise reciprocated vertically by any usual or suitable actuating connections with a horizontally disposed rotary actuating shaft 14. Cooperating with the needles 13 in the formation of lockstitches, are rotary loop-takers (not shown) which may be of any suitable construction.

Mounted on the head 11 are the usual rotary take-up disks 15 and 16 carrying the take-up elements 17 and 18, respectively, as well as the thread-confining rings 19 and 20.

Each of two needle threads 21, drawn from its supply (not shown), is threaded through a tube 22 mounted upon the bracket-arm head 11. From the lower ends of the tubes 22, the threads 21 are each led about one of the two tension devices designated generally as 23, from whence the threads are directed upwardly to be disposed between the take-up disk 16 and its associated thread-confining ring 20 to overlie the thread-engaging elements 18. From the elements 18, the threads pass forwardly between a face-plate 24 and the machine-head 11, over the thread-engaging elements 17 between the disk 15 and its associated ring 19. From the elements 17, the threads pass downwardly successively through the face-plate thread-guides 25 and 26 to be directed to the proper needle.

Further explanation of the present rotary take-up is not deemed necessary and, for a complete disclosure of the same, reference may be had to the U. S. patent of S. Zonis, No. 2,385,960, Oct. 2, 1945.

Referring more particularly to the present invention, each of the tension devices 23 comprises a cup-shaped support or sleeve member 27 which is seated within one of two apertures 28 formed in the head 11. A set-screw 29, threaded into the head, engages an annular groove 30 in the sleeve member 27 for the purpose of securing the latter element within the aperture 28. In the rear portion of the sleeve 27 is formed an aperture 31 for entrance by the reduced rear end 32 of a threaded stud or arbor member 33 which is secured within the aperture 31 by means of a set screw 34.

Slidably mounted upon an intermediate portion of the arbor 33 is an apertured abutment-plate 35 provided with two ears 36 which are bent about a circumferential flange 37 formed on the sleeve 27. These ears 36 preferably engage the flange 37 at diametrically opposite sides thereof and function as guides which permit the abutment-plate to turn about the arbor 33 but

which prevent the plate from canting on the arbor.

Extending rearwardly from the peripheral portion of the abutment-plate is a motion-restraining finger 38 which is adapted to enter one of the two apertures 39 formed within the face portion of the head 11.

Extending forwardly from the peripheral portion of the abutment-plate 35 is a thread-guiding finger 40, the function of which will be hereinafter described. Also extending forwardly from the peripheral portion of the plate is a thread-confining finger 41 which forms, in conjunction with the plate proper, a thread-confining notch or thread-guide 42.

Abutting against the outboard face of the abutment-plate is an inner disk 43 of a pair of spring biased and centrally apertured thread-tension disks mounted upon the arbor 33, the outer disk being designated by the number 44. Also mounted upon the arbor 33 is an anchor-disk 45 having a diameter-bar 46 passing through a slot 47 formed in the outer end of the arbor 33. The outer end-portion of the arbor 33 is also provided with threads 48 for a tension-adjusting thumb-nut 49 for the purpose of forcing a bee-hive spring 50 against the anchor-disk 45 which transmits the pressure of the spring directly against the disks 43 and 44. By adjusting the thumb-nut 49 along the threaded portion of the arbor, the pressure existing between the disks 43 and 44 may be varied.

An endwise movable tension-release pin 51 is supported in a longitudinal bore 52 of the arbor 33. The forward end of this pin 51 is adapted to engage the diameter-bar 46 of the disk 45 and the rear end thereof is adapted to be engaged by a cam-lever 53 which is actuated by the usual presser-foot lifting lever 54. This tension-release pin 51 operates in the usual manner in that it is adapted to be pushed by the cam-lever in a direction to relieve the tension-disks 43 and 44 of the pressure of the tension-spring 50. Fig. 10 illustrates the positions assumed by the disks when relieved of the spring pressure.

Referring to Fig. 4, the sleeve 27 has a cylindrical aperture 55 in which is disposed an enlarged portion 56 of the arbor member 33 having a slot 57 formed longitudinally thereof. Coiled about this enlarged portion 56 is the usual torsion check-spring 58, one end 59 of which is anchored in the slot 57. The other end of the torsion check-spring is extended outwardly at 60 through a segmental clearance opening 27' formed in the outer end of the sleeve 27. At its free end, the outwardly extending arm 60 of the spring is bent backwardly to form a thread-engaging loop 61. The arm 60 of the check-spring is limited in its movement in one direction by a stop-ledge 62 forming one wall of the segmental opening 27' of the sleeve 27. Circular adjustment of the sleeve 27, within the machine aperture 28, determines the stopped position of the looped end 61 of the check-spring. The tension of the check-spring may be adjusted by loosening the set-screw 34 and turning the arbor 33 in its socket in the supporting sleeve 27 and by subsequently tightening the screw 34.

Referring to Fig. 6, the flange 37 of the sleeve 27 is provided with a notch 63 for the purpose of facilitating placement of the abutment-plate 35 in its proper position relative to the sleeve. Thus, when assembling the sleeve and abutment-plate together, one of the ears 36 of the latter unit may enter the notch 63, thereby permitting the ears 36 to be bent prior to the assembly operation.

Referring to Fig. 1, the tension unit is disclosed in its operable condition. The thread 21 passes over the thread-guiding finger 40, then about the arbor 33 between the disks 43 and 44, and then is directed through the thread-confining notch 42 from which it passes under and about the check-spring before being directed to the take-up elements. By thus passing the thread about the thread-guiding finger 40 before passing the same between the disks, the thread is prevented from fouling the check-spring.

From the above description, it is to be understood that the present abutment-plate 35, with its guiding ears and motion-restraining finger, is not only restrained from turning about the sleeve 27 but, at the same time, it has no tendency to cant.

Considered circumferentially of the guard-plate 35, the stop-finger 38 thereof is located between the thread-guiding finger 40 and the thread-confining notch 42; the latter being located between the stop-ledge 62 of the sleeve 27 and the stop-finger 38. As the arm 60 of the check-spring is confined to vibratory movement between the stop-ledge 62 and the stop-finger 38, the check-spring cannot foul the portion of the thread directed from the tube 22 to the tension device by the thread-guiding finger 40 which is disposed at the side of the stop-finger 38 opposite to the check-spring side thereof.

Figs. 5, 7 and 9 disclose a modified form of the present tension unit. This modified unit is exactly the same as the above described unit but for an addition of a check-spring guard element.

Referring to Figs. 5 and 7, a check-spring guard element 64, having a generally dished shape, is inserted between the outer disk 44 and the anchor-disk 45. Projecting upwardly from the periphery of this dished element are a pair of ears 65 which, when the element is assembled, embrace the thread-guiding finger 40, thus to prevent rotation of the element. Also provided in the periphery of this element is a slot 66 through which extends the free end portion 67 of the check-spring 58. Referring to Fig. 9 it is to be seen that by so inserting the portion 67 of the check-spring within the slot 66, the possibility of the thread 21 disengaging itself from the check-spring loop 60 becomes rather remote. Therefore, the present guard 64 is particularly useful whenever an excess of slack occurs in the thread 21, as this element will prevent inadvertent unthreading of the check-spring.

Having thus set forth the nature of the invention, what we claim herein is:

1. In a thread tensioning device for sewing machines, a support formed with a flange, an arbor carried by said support, spring-pressed opposed tension-disks mounted upon said arbor, a thread-guide carrying abutment-plate disposed adjacent one of said tension-disks, and interlocking means between the flange of the support and the abutment-plate providing for relative turning adjustment of said support and abutment-plate and for confining said abutment-plate against sidewise movement.

2. In a thread tensioning device for sewing machines, a cylindrical supporting member having a circumferential flange, an arbor carried by said supporting member, releasable thread tensioning means mounted upon said arbor, a thread-guide carrying abutment-plate disposed adjacent said thread tensioning means, and ears extending from said abutment-plate and bent about said flange of the supporting member.

3. In a thread tensioning device for sewing

machines, a supporting member having a stop-shoulder, an arbor carried by and projecting from said supporting member, releasable thread tensioning means carried by said arbor, a thread-guide carrying abutment-plate disposed between said tensioning means and said supporting member, a check-spring having a thread-controlling arm yieldingly engaging said stop-shoulder, and abutment-plate confining means comprising interlocking members between said support and said abutment plate which provide for relative turning adjustment of said supporting member and abutment-plate about the longitudinal axis of said arbor and for restraining said abutment-plate against sidewise movement upon release of said thread tensioning means.

4. A sewing machine tension device having an arbor, thread tensioning means mounted on said arbor, a thread-controlling check-spring having one end thereof anchored to said arbor and having a thread-engaging free-end portion, an abutment-plate disposed at one side of said tensioning means and provided with a thread-guide in the region of the thread-engaging portion of said check-spring, a guard-plate mounted upon said arbor at the opposite side of said tensioning means in position to house the free end of said check-spring, and interengaging means carried by said abutment-plate and guard-plate for preventing relative turning movement thereof about said arbor.

5. A sewing machine tension device having an arbor, thread tensioning means mounted on said arbor, a thread-controlling check-spring anchored to said arbor at one side of said tensioning means, said check-spring having a free end thread-engaging portion bent about and extending to the opposite side of said tensioning means, means housing the free end of said check-spring and consisting of a flanged guard-plate mounted upon said arbor for movement endwise thereof, and means comprising a stationary finger extending across said tensioning means for restraining said guard-plate from turning about said arbor.

6. A sewing machine tension device having an arbor, thread tensioning means mounted on said arbor, a thread-controlling check-spring having a thread-engaging free end portion, an abutment-plate at one side of said tensioning means and provided with a thread-guide for directing the thread from said tensioning means to said check-spring, means housing the free end of said check-spring and comprising a guard-plate mounted on said arbor at the side of said tensioning means remote from said abutment-plate, and a finger connecting and providing for relative movement of said abutment-plate and guard-plate.

7. In a thread tensioning device for sewing machines, an arbor, thread tensioning means carried by said arbor, a thread-controlling check-spring having one end anchored to said arbor and having a yielding thread-engaging portion, a stationary abutment-plate provided with laterally extending stop means limiting movement of the thread-engaging portion of the check-spring responsively to the pull of the thread thereupon, a laterally extending lead-in thread-guide carried by said abutment-plate at one side of said check-spring stop means, and a laterally extending lead-out thread-guide carried by said abutment-plate at the other side of said check-spring stop means.

8. In a thread tensioning device for sewing machines, an arbor, thread tensioning means carried by said arbor, a thread-controlling check-spring having a yielding thread-engaging portion, 5 and an abutment plate disposed adjacent said thread tensioning means, said abutment plate having a stop-finger projecting laterally from one side of said plate and disposed to be engaged by said check-spring, and a pair of thread-guides 10 projecting from the other side of said abutment-plate and spaced on opposite sides of said stop-finger.

9. In a thread tensioning device for sewing machines, an arbor, thread tensioning means carried by said arbor, a thread-controlling check-spring having one end anchored to said arbor at one side of said thread tensioning means and having a free end thread-engaging portion bent about and extending to the opposite side of said 15 thread tensioning means, and means for housing the free end of said check-spring, said means including a guard-plate formed with a laterally extending flange slotted to provide an opening through which the free end of the check-spring 20 extends, and means for restraining said guard-plate against turning about said arbor.

10. A releaseable tension device for sewing machines, comprising, a supporting sleeve having at one end thereof a clearance opening and a circumferential flange, an arbor mounted in said sleeve for turning adjustment and extending through the flanged end of said sleeve, a pair of opposed tension-disks mounted upon said arbor for movement endwise thereof, a check-spring 30 embracing said arbor within said sleeve, said check-spring being anchored to said arbor and having a reversely bent free end portion extending through said clearance opening of the supporting sleeve and about the peripheries of said tension-disks, thereby to provide a yieldable thread-engaging loop, an abutment-plate mounted upon said arbor between said tension-disks and the flanged end of said sleeve, said abutment-plate having a primary stop-finger overhanging 35 said sleeve and an oppositely directed secondary stop-finger overhanging said tension-disks, means for preventing canting of said abutment-plate comprising abutment-plate ears embracing said flange, a thread-confining finger extending 40 from said abutment plate toward and having its free end spaced from said secondary stop-finger, a guard-plate mounted upon said arbor at the side of said tension-disks opposite to said abutment-plate, said guard-plate having a slotted flange entered by and housing the free end of 45 said check-spring, and said guard-plate having a peripheral stop-notch entered by said secondary stop-finger, and spring means for yieldingly pressing said tension-disks towards each others.
